SERVING ATTACHMENT FOR A JAR OR SIMILAR ARTICLE

Everett A. Johnson, 15 S. Prospect Ave., Park Ridge, Ill., and Rose Marie Ann Bragiel, 4224 Henry St., Hammond, Ind.

Filed Aug. 29, 1963, Ser. No. 76,384

Term of patent 14 years

(Cl. D58—26)

FIGURE 1 is a top plan view of a serving attachment for a jar or similar article embodying our new design;

The portions shown in broken lines are for illustrative purposes only.

We claim:

The ornamental design for a serving attachment for a jar or similar article, as shown and described.
